UNITED STATES PATENT OFFICE

2,504,891

SUPPORTING AND POSITIONING DEVICE
FOR CAR COUPLERS

Vinton E. Sisson, Chicago, Ill., assignor to Standard Railway Equipment Manufacturing Company, Chicago, Ill., a corporation of Delaware

Application October 31, 1946, Serial No. 706,984

4 Claims. (Cl. 213—61)

1

This invention relates to coupler supporting and positioning devices for railway car couplers, and more particularly to means to swingably and resiliently support a railway car coupler in such manner that when the coupler is uncoupled, said coupler is maintained by the device in substantially the longitudinal central plane of the car, or in what is known in the trade as "coupling range."

More specifically the device comprises a coupler carrier pivotally supported at its ends by links which are pivotally, swingably and resiliently supported from a member adapted to be fixed to a railway car, such as a striking casting, as shown in the drawings. To provide such a device for so supporting a coupler and maintaining it when uncoupled within said "coupling range" is the principal object of the invention.

Broadly such a device is shown and claimed in my copending applications, Serial No. 706,983 and Serial No. 706,985, and the claims herein are accordingly restricted to the invention illustrated and described herein.

Another object of the invention is to provide such a cushioned coupler support and positioning device wherein should the cushioning means fail for any reason the device would nevertheless function as a coupler support and positioning device. In other words, should a spring break the coupler would still be swingably supported and be returned to "coupling range" by the device.

A further object of the invention is to provide such a cushioned coupler carrier and positioning device of the swing motion type wherein the cushioning means is not materially distorted during the swinging of the device.

The term "resilient means," as used in the specification and claims, is intended to cover springs, rubber, or any other resilient material. Most of these materials, if intermittently compressed to excess progressively lose their effectiveness, and, consequently, it is a further object of the invention to provide means to limit the compression of said resilient means.

In the drawings:

Figure 1 is a vertical section partly in elevation of one half of a coupler carrier embodying the invention.

Figure 2 is a top plan view of Figure 1.

Figure 3 is a section on line 3—3, Figure 1.

Figure 4 is a perspective view of a part of the striker structure showing one-half of the bracket portion for supporting the link assembly.

Figure 5 is a sectional view similar to Figure 1 but of the whole device showing the parts as they would appear when the coupler had moved to one side its maximum distance.

Figures 6, 7 and 8 are, respectively, side elevation, top plan and end view of the link supporting spring cap.

2

Figure 9 is a top plan view of one end of the coupler carrier.

Figure 10 is a section on line 10—10, Figure 9.

Figures 11 and 12 are, respectively, side elevation and plan view of the link.

Figure 13 is a view similar to Figure 1 with the resilient means omitted to illustrate that in such case the device still functions as a swingable coupler support and positioning device.

In the drawings the striking casting is formed of two spaced plates 1 and 2 joined together and maintained in spaced relation by webs 3 and 4. Plates 1 and 2 are generally of like rectangular form and are each provided with a substantially central rectangular opening 5 through which the shank 6 of a railway car coupler projects and in which said coupler is vertically, laterally and longitudinally movable. The striker is, of course, fixed in any suitable manner to the end structure of the car, usually to the end of the center sill, and said striker may be of an integral casting or built up of welded parts, as preferred. The web 4 is continuous from substantially side to side of the striker adjacent the bottom thereof, and the web 3 is of channel-like shape extending about the upper edge 7 of the springs 5 and partially down the sides thereof and provided with a lateral flange or shelf 8 extending substantially to the side edge of the striker. Through end flange or shelf 8 is a rather large downwardly and outwardly tapering hole 9, and projecting upwardly from each of said flanges 8 is an annular spring seat embossment 10. Projecting inwardly from plate 1 and also plate 2, are two oppositely disposed identical shelf-like bracket portions each comprising spaced walls 11 and 12, and a shelf-like portion 13. The outer edge of each shelf-like portion 13 has a segmentally shaped portion 14 removed therefrom. These shelf-like portions project toward each other and in alignment with each other but do not meet, being spaced from each other. Mounted upon each flange 8 within the spring seat embossment 10 is a tapered coil spring 15, the lower convolution of which is larger in diameter than the hole 9 so that the spring rests within the embossment 10 upon flange 8 about the hole 9 therethrough. The axis of the spaced segments 14 and of the hole 9 coincide, and each spring 15 is of a length to project upwardly between said segments 14 thereabove. Upon the upper end of said spring 15 rests the rectangular spring cap 16 which moves vertically between said walls 1, 2, 11 and 12, and is guided thereby against lateral movement due to service movements of the car. An embossment 17 projects downwardly from the rim of spring cap 16 so as to provide a hollow therewithin for the upper convolution of said spring 15, to hold said spring in place. Through the spring caps is provided a rectangular hole 18, which is elongated in a direction transversely of

the device, and adjacent each of the longer sides is an upstanding triangularly shaped flange 19, each having a hole 20 therethrough, which holes 20 are in alignment with each other. Flanges 19 are each provided with reflanges 18' extending at an angle to the edge of the body portion of said spring cap. These holes are for application of a journal pin 21 therethrough. A coupler support suspending link 22, having an eye 23 formed at one end and a T formation at the other end 10 providing oppositely extending trunnions 24, is inserted through the aligned holes 9, 14 and 18, and the spring with the eye portion 23 extending between the flanges 19 so that the pin may be inserted through the holes 20—20 and the eye 23 and thereby hold the link in place as well as the spring cap upon the upper end of the spring. It will be noted that the pin 21 is in length substantially equal to the distance between walls 1 and 2 and consequently in order to insert the pin in position a hole 25 is provided through wall 1 for this purpose. The link 22 thus is resiliently suspended pivotally at a point above the shelf or flange 8, and projects downwardly through hole 9 to a point therebelow. In Figure 6 it will be seen that the holes 20 in flanges 19 are located so that when pin 21 is inserted therethrough the ends of the pin will also bear on the surface of the spring cap 16 (see Fig. 3) in consequence of which the bearing holes 20 are not taking the entire load.

The coupler carrier is shown at 30 and is positioned between walls 1 and 2. Carrier 30 is of channel-like form, the top or web 31 of which is depressed centrally, as at 32, in which depressed portion the coupler shank is designed to rest and be supported. Flanges 33 depend from either side of the carrier and provide the necessary strength for said carrier. At its opposite ends the carrier is hook-shaped, as at 33', and bifurcated so as to straddle the links 22 with each hook shaped or bearing portion resting upon a trunnion 24 at the lower end of link 22. Thus the coupler 6 resting upon the carrier, which in turn is supported by the links, is resiliently supported and in addition may move laterally within the limits of the opening 5. When the coupler moves laterally the carrier 30 is correspondingly moved, thus swinging the links 22 on pins 21 (see Fig. 5) and causing the spring cap to tip slightly. For this reason the edges of the spring cap are slightly convex so that when tipped there will be no binding between walls 11 and 12, or 1 and 2, and thus the spring cap may freely reciprocate vertically between said walls. Should the coupler be uncoupled during a time when it has moved laterally, as shown in Figure 5, since the weight of the coupler in this position is to one side of the axis of pins 21, the coupler will swing back like a pendulum until the links are substantially vertical due to the combined action of gravity and momentum.

The spring 15 is of a length and strength relative to the weight of the coupler and carrier so as to normally maintain the spring cap approximately one-half inch above the shelf-like portion 13, and thus all road shocks which move the coupler downwardly a distance less than the space between the spring cap and shelf 13 are absorbed by the springs. When, however, the coupler is affected by a violent shock, the spring caps would descend until they contacted the shelf-like portion 13, thereby preventing further downward movement and saving the spring from possible breakage.

Should the spring break, or even become lost, the most that could happen would be that the spring cap would then rest upon the shelf 13, and the device would still function as a coupler support and positioning device. This possibility is illustrated in Figure 13.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

- 15 1. In a device to swingably and resiliently support a coupler carrier from a member adapted to be fixed to a car, a link, one end of which is adapted to pivotally suspend one end of the carrier from said member, a spring cap having an opening therethrough through which the other end of said link extends, said other end of said link being pivotally connected to said cap, and resilient means interposed between said cap and said member to provide resilience to the pivotal suspension of said carrier.
- 20 2. Means to swingably and resiliently support a coupler carrier from a striking casting comprising a member and a stop adapted to be fixed to a car, said means comprising a link adapted to pivotally suspend one end of the carrier from said member; a spring cap having an opening therethrough through which one end of said link extends, means to pivotally connect said link to said cap, resilient means interposed between said cap and said member to provide resilience to the pivotal suspension of said carrier, and said stop and cap being constructed and arranged so as to limit the action of said resilient means without affecting the pivotal suspension of said carrier.
- 25 3. In a device to swingably and resiliently support a coupler carrier from a member adapted to be fixed to a car, said member including a shelf having an aperture therethrough, a link passing through said aperture, one end of said link being adapted to pivotally suspend one end of the carrier, resilient means about said link and resting upon said shelf around said aperture to provide resilience to the pivotal suspension of said carrier, and a spring cap for said resilient means pivotally connected to the other end of said link.
- 30 4. In a device to swingably and resiliently support a coupler carrier from a striking casting adapted to be fixed to a car, said striking casting having a shelf integrally formed therewith and having an aperture therethrough, a link extending through said aperture, one end of said link being adapted to pivotally suspend one end of the carrier from said shelf; a cap pivotally connected to the other end of said link, resilient means interposed between said cap and said member about said link to provide resilience to the pivotal suspension of said carrier, and means on said shelf to guide said cap against lateral movement due to service movements of the car.
- 35 5. VINTON E. SISSON.
